UNITED STATES PATENT OFFICE.

DE LANCEY A. CAMERON, OF GENESEO, NEW YORK, ASSIGNOR TO DELAC PLASTER CO.,
OF MUMFORD, NEW YORK, A CORPORATION OF NEW YORK.

PLASTER-BOARD.

1,028,931.

Specification of Letters Patent. Patented June 11, 1912.

Application filed October 31, 1911. Serial No. 657,832.

To all whom it may concern:

Be it known that I, DE LANCEY A. CAMERON, a citizen of the United States, and resident of Geneseo, in the county of Livingston and State of New York, have invented certain new and useful Improvements in Plaster-Boards, of which the following is a specification.

This invention relates to boards or sheets 10 of plastic composition such as are employed in place of lathing and plaster.

The object of the invention is to produce a plaster-board having reinforcing devices of simple and inexpensive form, for the purpose of reinforcing the board, particularly at its edges and corners, while at the same time affording secure anchorages for the nails or screws by which the board is fastened in place.

20 To this end the invention consists in a plaster-board having the novel form of reinforcement hereinafter described, as the same is defined in the succeeding claims.

In the accompanying drawings:—Figure 25 1 is a front-elevation of a plaster-board embodying the present invention, with a portion broken away to show the interior construction; and Fig. 2 is a sectional view, on the line 2—2 in Fig. 1, but on a larger scale, 30 showing in detail the construction of the reinforcement at a corner of the board.

The invention is illustrated as embodied in a plaster-board of ordinary form and of any convenient size, having a body 3 formed of any ordinary or suitable plastic composition such, for example, as a mixture of plaster and fibrous material. This body may be reinforced throughout in the usual manner by a netting 4 of fine wires.

40 The invention resides particularly in the means by which the edges and corners of the board are reinforced, and by which anchorages are provided for the nails or other fastening means. To this end I provide, 45 throughout the periphery of the body 3, a marginal reinforcement in the form of comparatively heavy wires 5. These wires do not extend continuously through the periphery of the board, but comprise separate, 50 straight lengths which are fixed at their ends to metal plates or corner-pieces 6. The corner-pieces are preferably embedded at the middle of the thickness of the body, and are formed to extend outwardly to, or substantially to, the corner of the body, as

shown in Fig. 1. These corner-pieces are perforated to receive the ends of the wires 5, which are passed through the perforations and twisted upon themselves. The corner-pieces serve not only as connections and anchorages for the wires 5, but they also rigidly reinforce the corners of the board to the very apices of the angles, where they are most liable to injury. This is a feature of great practical advantage, as it has been found that in the shipping and handling of plaster-board the corners are the parts most frequently broken away. By reinforcing the corners and preventing such accidental breakage I am enabled to use my plaster-board in a novel and economical manner, namely, without the use of pointing. That is to say, it is necessary only to fit the plaster-board carefully in place upon the studing or framework of the building, and thereafter to spread a finishing coat of plaster upon the boards by means of a brush. Owing to the square edges and corners, the boards make close joints at all points, and therefore the use of a finishing coat of plaster spread as described is sufficient to close these joints and make a smooth, unbroken surface for the reception of paint or wall paper. In order that the corner-pieces 6 may serve also as anchorages for the nails 85 or fastening devices, they are extended into the body of the board within the wires 5, as shown in Fig. 1, and provided with perforations 8 to receive the nails. The body of the board is preferably provided also 90 with perforations 9 registering with the perforations 8 so as to receive the nails without danger of splitting the body, and the front surface of the board is also preferably provided with recesses 10 of greater diameter to 95 receive the heads of the nails.

It will be apparent that by the arrangement just described I am enabled to provide anchorages for the nails which are located at a sufficient distance within the edges of the board to support the strain of the nails without cracking away the corners of the board, while at the same time I provide anchorages by which the marginal wires 5 are supported very close to the edges of the boards, thus most effectually reinforcing these edges.

As it is frequently necessary to subdivide a plaster-board of standard size into smaller panels, to fit spaces of less than the full size 110

of a board, the illustrated embodiment of the invention has provision for thus subdividing the board into two or four panels, each of which, after such division, is reinforced throughout all of its edges and corners. To this end the marginal reinforcements are divided midway in each edge of the board by a metal plate 12 to which the wires 5 are anchored. This plate is of such form that when divided centrally by means of a saw-cut or otherwise, as indicated by the dot-and-dash lines in Fig. 1, it produces two corner-pieces substantially similar in form to the corner-pieces 6, and these pieces are provided with nail-receiving perforations in the same manner as the pieces 6. To reinforce the cut edges of the panels wires 11 are provided, these wires being connected with the pieces 12 in the same manner as the wires 5. At the middle of the board a pair of plates, similar in form to the plates 12, are used, as shown in dotted lines in Fig. 1.

I claim:

- 25 1. A plaster-board comprising a panel of plastic composition, sheet-metal anchorages embedded in the panel adjacent its corners and extending outwardly approximately to the edges of the panel, the anchorages being provided with nail-receiving perforations, and reinforcing wires embedded in the panel parallel with, and close to, its edges and fixed at their ends to the anchorages.
- 30

2. A plaster-board comprising a panel of plastic composition, sheet-metal anchorages 35 embedded in the panel adjacent its corners and extending outwardly approximately to the edges of the panel, the anchorages being provided with nail-receiving perforations located at a substantial distance within the 40 edges of the board, and reinforcing wires embedded in the panel parallel with, and close to, the edges thereof and fixed to the anchorages at points nearer to the edges of the board than said nail-receiving perforations. 45

3. A plaster-board comprising a panel of plastic composition, reinforcing wires embedded in said panel and extending parallel with, and close to, the edges thereof, and 50 anchorages at the corners of the panel, each anchorage comprising a piece of sheet-metal embedded in the panel substantially parallel with and intermediate its opposite surfaces, the anchorage extending from the extreme 55 corner of the panel inwardly, said wires being connected with the anchorages, and each anchorage extending inwardly beyond its points of connection with the wires and being provided, in said inward extension, 60 with a nail-receiving perforation.
